DESIGN FOR A CLIP BOARD

John Henry Brinker, Covington, Ky., assignor to
The Globe-Wernicke Company, Norwood, Ohio,
a corporation of Ohio

Application December 4, 1942, Serial No. 108,945

Term of patent 14 years

To all whom it may concern:

Be it known that I, John Henry Brinker, a citizen of the United States and a resident of Covington, in the county of Kenton and State of Kentucky, have invented a new, original, and ornamental Design for a Clip Board, of which the following is a specification, reference being had to the accompanying drawing, forming a part thereof.

In the drawing:

I claim:

The ornamental design for a clip board, as shown.

JOHN HENRY BRINKER.
